M. ANUNDI

LOCK

Filed August 9, 1924

Patented Feb. 16, 1926.

1,573,506

UNITED STATES PATENT OFFICE.

MATT ANUNDI, OF CLATSASKIE, OREGON.

LOCK.

Application filed August 9, 1924. Serial No. 731,075.

To all whom it may concern:

Be it known that I, MATT ANUNDI, a citizen of the United States, and a resident of Clatsaskie, county of Columbia, State of Oregon, have invented a new and useful Improvement in Locks, of which the following is a specification.

My invention relates to locks of the class provided with a sliding bolt, and with a swinging tumbler having a notch in its free end, adapted to engage the blade of the proper key, at such an angle and position that the thrust resulting from the rotation thereof will be transmitted to the sliding bolt to force the latter back against a spring, and thus disengage the bolt from its keeper.

The object of my invention is to provide a lock of this character which is simple in operation, is inexpensive to manufacture and difficult to open except with knowledge of the correct operation thereof, and the use of the proper key, and I preferably provide an alarm which signals each attempt to open the lock.

A further and incidental object of my invention is to provide a novel latch for holding the swinging tumbler out of operable position when the key is rotated in the wrong direction and which, by preventing the return of said tumbler to its normal operative position, prevents the door from being opened until such latching means is released.

A further object is to provide an alarm with this type of lock which consists preferably of two spirally coiled pieces of resilient wire, one at each side of the key hole, these coiled wire alarms being arranged so that the key must engage either before it can move into engaging position with the lock operating mechanism. As the key moves past either of the spirally wound alarms it engages the free end thereof for a short period of time and when it releases the same by passing beyond the alarm the resiliency of the spring produces a ring when it springs back to its normal position.

The details of construction and mode of operation of my device are hereinafter more fully described with reference to the accompanying drawings.

In the drawings:

Fig. 1 is a longitudinal section through the lock and illustrates that the blade of the key when inserted in the key hole must actuate either of the alarms in order to pass

to operating position with the lock operating mechanism, this section is taken on the line 1-1 of Fig. 2;

Fig. 2 is a transverse section taken approximately on the line 2-2 of Fig. 1 and shows the key with a portion broken away to illustrate a detail of construction;

Fig. 3 is an elevation of my improved lock with parts broken away to disclose the action of the lock on the swinging tumbler;

Fig. 4 is a similar view except that it shows the key having been rotated after engagement with the swinging tumbler to a position in which it has moved the sliding lock out of engagement with its keeper;

Fig. 5 is a similar view to the preceding figures and illustrates how the swinging tumbler is moved out of operative position and is held in that position when the key is rotated in the wrong direction; and

Figs. 6, 7 and 8 are detailed views illustrating structural features.

My lock is preferably made so that it is wholly contained within a casing *a* having a removable cover *a'* which is held thereto by screws *b*. The casing is adapted to be recessed within the side wall *c* of the container and the lid *d* which the lock holds closed is provided with a fixed keeper *e* having outstanding ears *e'* which pass through the apertured front piece *a²* of the casing to engage similar ears *f'* on the sliding lock bolt *f*. The bolt *f* is recessed at one side and engages therein a bar *f³*, arranged transverse of said casing. The space between said bar and said casing is such that a sliding fit is provided for said bolt.

The swinging tumbler *g* is pivotally connected to the pendent arm *f²* on the sliding bolt, being held upon a pin *f⁴*. The swinging tumbler has a pin *g'* extending outwardly therefrom and a coiled spring *h* is attached thereto which normally holds the swinging tumbler in the position shown in Fig. 1, which is, substantially aligned with the arm *f²* but slightly at an angle thereto. The free end of the swinging tumbler is provided with a notch *g²* with which the bit *i²* of the key *i* is adapted to engage.

The key is inserted into the lock through a key hole *j* and at one side of the key hole is an alarm *k* and at the other, an alarm *k'*, which consist of spirally wound coils of resilient wire. The extremities *k²* and *k³* respectively of the coils *k* and *k'* are arranged to lie in the path of the bit *i²* of the key

and thus to be engaged therewith during a portion of its rotation. When the bit moves by the extremities, it releases them and the resiliency of the wire, springs the coil back 5 to normal position and results in a pronounced ring which thus acts as a signal to indicate that someone is attempting to open the lock.

The key i is preferably provided with a 10 hollow barrel i^2 which is adapted to fit over the guiding pin l which is carried by a resilient spring-like member m . The depth of this hollow barrel is less than the length of the pin l , for the purpose hereinafter described.

The spring like member m is fastened at one end, as m' , to one side of the casing a and its other end m^2 is provided with a latching lug m^3 which extends through the 20 wall of the casing and is adapted to engage the swinging tumbler in one position, as shown in Fig. 5. When the tumbler is engaged by the latching lug, the lug can be moved out of engagement therewith only 25 by pressing upon the key and forcing the spring like member m outwardly, away from the wall of the casing. This is permitted because of the difference in length in the depth of the barrel and length of the 30 pin, hereinbefore referred to and clearly shown in Fig. 2. The member m normally lies flat, as shown in this figure, and is of relatively substantial strength. Thus, when the key is inserted in the lock and the bore 35 of the barrel of the key fits over the pin l , the member normally acts as a stop. To release the key it is necessary to use more pressure than would normally be used to open the lock and thus the latch would not 40 be inadvertently released by the uninformed. The flexure of the member m under the pressure of the key i is limited by the striking of the end of the key against the casing which separates them. This prevents 45 the elastic limit of said member from being exceeded which would result in permanent bending of said member and the improper engagement of the latching lug m^3 .

The bolt j is normally held in co-operative 50 relationship with the keeper e by a leaf spring n and to open the lock it is necessary that the bolt must be moved so as to flex the springs before it can be moved out of engagement with its keeper.

55 The operation of my lock is as follows:

The key i is placed in the key hole j as shown in Fig. 1 and should be moved in a counter clockwise direction to the position 60 shown in Fig. 3. In this position it has moved the swinging tumbler upwardly until the blade i^2 engages the notch g^2 in the tumbler and then by reversing the direction of the rotation of the key, that is in a clockwise direction, the bolt will be moved towards the right as viewed in Figs. 1, 3, 4

and 5 so as to be out of engagement with its keeper, as shown in Fig. 4. The angle that the swinging tumbler g makes with the arm f^2 in this position prevents the tumbler from rotating about its pivot and thus sustains 70 the thrust of the blade of the key in such a manner that it moves the bolt against the action of the spring n .

If, however, it is attempted to open the lock by inserting the key in the key hole 75 and moving it directly in a clockwise direction the blade will merely move the swinging tumbler into the position shown in Fig. 5, where it will be held by the latch m^3 and will permit the blade of the key to continue 80 its rotation without effecting the disengagement of the sliding lock band with its keeper. The key can then be rotated in either direction without affecting the locking mechanism.

Each rotation of the key blade, however, will engage and disengage the ends h^2 and h^3 of the coil springs, thus signalling that attempts are being made to open the lock. When the latch m^3 has engaged the swinging 90 tumbler it is necessary to press downwardly on the key as hereinbefore described to permit the swinging tumbler r to be returned to its normal position by the spring h .

I claim:

1. In a lock of the character described, a spring controlled slidable bolt adapted to engage a keeper, a tumbler pivotally attached to said bolt, resilient means for holding said tumbler in one position, a resilient latch adapted to engage and hold said tumbler when rotated in one direction, means for releasing said latch, and a guide for the key adapted for opening said lock, said guide and said latch being mounted 100 upon a common yielding device, whereby pressure applied to said key serves to release said latch.

2. In a lock of the character described, a spring controlled slidable bolt adapted to engage a keeper, a tumbler pivotally attached to said bolt, resilient means for holding said tumbler in one position, a resilient latch provided with a lug adapted to engage and hold said tumbler when rotated in one 110 direction, said latch provided with a pin, and a key provided with a barrel whose bore is shorter than said pin, whereby the key when pressed against said pin will move the latch to withdraw the same from engagement with said tumbler and means for limiting the movement of said latch by said key.

3. In a key operated lock, a casing, a bolt 125 slidably mounted in said casing, said casing adapted to permit the engagement of a keeper by said bolt, a spring normally holding said bolt in engaging position relatively to said keeper, a swinging tumbler pivotally attached to said bolt, a spring normally 130

holding said tumbler in one position, said tumbler having means on its free end adapted to be engaged by the bit of a key used for opening said lock when said key is turned in one direction, and a latch adapted to engage said tumbler and hold the same out of the path described by the bit of the

key when turned in a direction opposite to the one to open said lock, said guide and latch being connected by a common yielding member whereby the yielding of the guide serves to release said latch. 10

MATT ANUNDI.
